UNITED STATES PATENT OFFICE.

JULIUS H. RICHARDS, OF NEWARK, NEW JERSEY, ASSIGNOR TO SPLITDORF ELECTRICAL COMPANY, OF NEWARK, NEW JERSEY.

COMBINED GENERATOR AND TIMER-DISTRIBUTER MOUNTING.

1,142,056.

Specification of Letters Patent.

Patented June 8, 1915.

Application filed December 22, 1914. Serial No. 878,534.

To all whom it may concern:

Be it known that I, JULIUS H. RICHARDS, a citizen of the United States, residing at Newark, county of Essex, and State of New Jersey, have invented certain new and useful Improvements in Combined Generator and Timer-Distributer Mountings, of which the following is a specification.

The object of this invention is to provide a means for mounting both a timer-distributer and a generator on a suitable mounting in such a manner that either one may be removed without disturbing the other or the driving connections thereto. The timer-distributer is used in connection with a battery and induction coil for the purpose of furnishing sparking in the cylinders of an internal combustion engine, while the generator is used to charge the battery. Both of these pieces of apparatus are driven from the engine through suitable driving means. Heretofore it has been customary to mount these pieces of apparatus separately or in such a combination that the individual units cannot be disassembled without disturbing the other. So far as I am aware, I am the first to introduce a combination such that the generator may be removed leaving the timer-distributer working and consequently leaving the engine in a condition to perform its function. Of course, the removal of the timer-distributer itself will put the engine out of commission, but another may be readily substituted and this substitution does not entail the dismounting of the generator or the entire mounting upon which both units are supported.

Other and further objects of my invention will be readily understood by anyone skilled in the art from a consideration of the following description, taken in connection with the drawings, wherein—

Figure 1 illustrates a side elevation of the mounting with the timer-distributer and generator attached thereto and the mounting fastened to a suitable support. Fig. 2 is an end view of Fig. 1 with the timer-distributer removed. Fig. 3 is a part elevation and part section on the line 3—3 of Fig. 2. Fig. 4 is part sectional and side elevation of one form of my invention, in which the generator is directly connected with the driving shaft, without any intermediate gearing. Fig. 5 is a top plan view of Fig. 4, but having the end housing shown in sec-

tion. Fig. 6 is a section on the line 6—6 of Fig. 4.

Referring now particularly to the drawings, 1 is the side of an engine crank case.

2 is a shaft projecting from some portion 60 of the engine, such as the timing gear case.

3 is a mounting having two flanges 4 and 5. These flanges are substantially at right angles to each other, 4 projecting downward

and is used to fasten the mounting to a suitable support, such as the engine crank case 65 1 or some part of the frame. Bolts 45 are used for this purpose. To the flange 5 is

fastened a generator 7 having an armature 37 and a commutator 38. In the form shown 70 in Fig. 3, the generator has an end bearing plate 10 fastened to the frame by screws 11.

This end bearing plate has a hub 12 projecting outwardly and through an opening in flange 5 into the hollow portion of the 75

mounting 3 and has a bearing 13 with 80 in the hub for supporting the shaft 14.

15 is suitable packing to prevent oil and grease from the bearing working back into the generator housing. The shaft projec- 85

tion 14 has a gear 16 mounted thereon, and held in place by a key 17 and nuts 18. On the end of the driving shaft 2 is

mounted a sleeve 19 and attached thereto 90 preferably in an integral manner are two 85

gears 20 and 21.

21 is adapted to mesh with gear 16, and 20 is adapted to mesh with gear wheel 26,

which is mounted on, or is integral with the 95 stub shaft 25, shown in Fig. 6. One end (a) of the stub shaft rests in the support 29,

which serves as a combined bearing and 100 thrust collar, which is attached to a circular part 6 of the mounting 3. As shown in Fig. 6, the bearing and thrust collar 29 is screwed

into the circular portion 6 and has thin washers 30 between its head and circular portion 6. These washers are used for the

purpose of adjusting the bearing and thrust collar 29 so as to get perfect engagement of 105 the gear wheel 26 with the gear 20.

The upper end (b) of stub shaft 25 is guided by the removable thrust bearing 27,

which is attached to the circular part 6 by any suitable means, such as screws 28. 8 110

is a timer-distributer block, which incloses the working mechanism for making and breaking the circuit through the induction coil and for distributing the high tension

current from the coil to the conductors 36, 115

which are attached to the terminals 33 by passing within the same and being partially held in place by a flexible cap 34, which is adapted to snap into grooves 45. The mechanism of the timer-distributer forms no part of my invention and it is not further described.

The timer-distributer has a shaft projection terminating in the enlarged portion 9. 10 The stub shaft 25 is adapted to project into one end of the enlarged portion 9 which is hollowed out to receive it and is held in place therein by the said set screws 32. The opening into the housing of the mounting 15 for the entrance of shaft 25 is closed by the cap 22 held in place by screws 23.

24 shows a means of getting oil to the shaft 2.

Referring to Fig. 3, it will be readily seen 20 that when the nuts 40 are removed from the stubs 39, that the generator 7 with the gear 16 which is attached to the generator shaft 14 can be removed bodily from the mounting without disturbing the timer-distributer 25 and since the means for driving the timer-distributer is still not disturbed, the engine can be kept running. It is also seen by reference to Fig. 4 that the removal of the nuts 40 from the stubs 39 allows this form of 30 generator to be removed without disturbing the driving connections of the timer-distributer 8. In this form the shafts 2 and 14 are keyed by keys 44 and 43 to sleeve 31.

Referring to Fig. 6, it is seen that the 35 thrust collar 27 can be pulled out, after the set screws 32 are loosened and the timer-distributer is taken off the stub shaft 25; and the hollow stub shaft 25 with its gear 26 can be withdrawn and the removal of 40 these parts in nowise disturbs the driving connections of the generator which is used for charging the storage battery.

In the form shown in Fig. 4, an additional flange 41 is cast integral with the mounting 45 for the purpose of fastening this type of generator with bolts 42 entering from the bottom.

Various changes may be made in the details, the broad features of which are herein 50 shown and described but such changes will, I believe, come within the scope of the appended claims.

Having thus described my invention, what I claim is:

55 1. In a device of the character described, in combination, a generator, a timer-distributer, means for driving said generator and timer-distributer, a mounting plate adapted to receive the said generator and said timer-distributer, means for holding said generator onto said mounting, whereby when said means are removed said generator may be removed from said mounting without disturbing said timer-distributer, as described.

60 2. In a device of the character described,

in combination, a generator, a timer-distributer, a driving shaft, a mounting common to both said generator and timer-distributer, said mounting having a flange to which said generator is detachably mounted, a shaft for 70 said timer-distributer, a gear on said shaft, a gear on said driving shaft and meshing with said gear on the timer-distributer shaft, a housing for said gears integral with said mounting, a second flange on said mounting 75 for supporting the mounting, the generator and the timer-distributer, substantially as described.

3. In a device of the character described, in combination, a generator having shaft extension, a timer-distributer having a shaft extension, a mounting common to both said generator and said timer-distributer, a housing integral with said mounting, a driving shaft extending into the housing on 80 one side, said generator shaft extension extending into the housing on the opposite side to said driving shaft, said timer distributer shaft extension entering said housing at right angles to the said driving shaft, 85 means within said housing for drivingly connecting the three said shafts, said mounting having a flange for detachably supporting said generator and a second flange for supporting all of said parts, substantially as 90 described.

4. In a device of the character described, in combination, a mounting having two flanges and a gear housing integrally connected, a generator having a drive shaft 100 adapted to be detachably fastened to one of said flanges, the other of said flanges being adapted to fasten the said mounting to a suitable support, a timer-distributer mounted above said housing and on a shaft extending into the housing, a drive shaft entering said housing and means within said housing for drivingly connecting the said three shafts.

5. In a device of the character described, 110 in combination, a mounting having two flanges substantially at right angles to each other and a housing, a generator having a drive shaft, one of said flanges adapted to have said generator rigidly fastened thereto, a support, the other of said flanges adapted to be fastened to said support, said housing adapted to have a timer-distributer mounted above it and having a shaft extending thereinto, a driving shaft extending 115 into said housing and means within said housing for connecting the generator and timer-distributer shafts to said driving shaft.

6. In a device of the character described, 120 in combination, a mounting having two flanges and a gear housing integrally connected, a generator having a driving shaft extending into said housing and adapted to be attached to one of said flanges, a sup- 125

130

port, the said second flange adapted to be rigidly fastened to said support, said housing adapted to have a timer-distributer mounted above it, and having a shaft extending thereinto, a main driving shaft extending into said housing, a gear on said shaft, a gear on said timer-distributer shaft and adapted to be meshed with the first mentioned gear, a removable thrust bearing 10 for said timer-distributer, and an adjustable bearing and thrust collar for said timer-distributer shaft and means within said housing to connect said main driving shaft to said generator.

15 7. In a device of the character described, in combination, a mounting having two flanges substantially at right angles to each other and a housing, an opening into said housing through one of said flanges, a support, the other of said flanges adapted to be rigidly fastened to said support, a generator having a driving shaft adapted to enter said housing through the opening through the first mentioned flange, said generator being removably attached to said flange, an opening into said housing on the opposite side from the first mentioned opening, a cap adapted to close the last mentioned opening, a gear mounted on said main driving shaft, a stub shaft having a gear thereon adapted to mesh with the first mentioned gear, a timer distributor adapted to be mounted on said stub shaft and means on said main driving shaft to connect the same 30 with said generator shaft, substantially as described.

8. In a device of the character described, in combination, a mounting having two flanges substantially at right angles to each other and a housing, an opening into said housing through one of said flanges, a support, the other of said flanges adapted to be rigidly fastened to said support, a generator having a driving shaft adapted to enter said housing through the opening through the first mentioned flange, said generator being removably attached to said flange, an opening into said housing on the opposite side from the first mentioned opening, a main driving shaft extending into the housing through said opening, a cap adapted to close the last mentioned opening, a gear mounted on said main driving shaft, a stub shaft having a gear thereon adapted to mesh with the first mentioned gear, a removable thrust bearing for said stub shaft, an adjustable bearing and thrust collar for said stub shaft and a timer-distributer mounted on said stub shaft.

60 9. In a device of the character described, in combination, a mounting having two flanges substantially at right angles to each other and a housing, an opening into said housing through one of said flanges, a generator adapted to be detachably mounted on

said flange and having a driving shaft extending into said housing, a gear on said generator shaft, a support, two flanges adapted to be rigidly fastened to said support, a second opening in said housing on 70 the opposite side from the first mentioned opening, a main driving shaft adapted to enter the last mentioned opening, means for closing said opening around said shaft, a stub shaft, a removable thrust bearing for 75 one end of said stub shaft and a combined adjustable bearing and thrust collar on the other end of said stub shaft, and means for driving said stub shaft from the main driving shaft, a gear wheel mounted on said 80 main driving shaft and adapted to mesh with the gear wheel on said generator shaft, a timer-distributer and means for attaching same to the stub-shaft.

10. In a device of the character described, 85 in combination, a mounting having two flanges and a housing integrally connected, an opening into said housing through one of said flanges, a generator having an end plate with a hub thereon and a driving shaft 90 projecting through said hub, a bearing within said hub for said shaft, said hub and shaft projection extending into the housing through the opening in said flange, and means for detachably fastening said generator to said flange, a support, said second flange adapted to be rigidly fastened to said support, a second opening into said housing, a main driving shaft extending through said opening into the housing, a stub shaft 100 mounted within said housing, a timer-distributer detachably fastened to said stub shaft, a gear on said stub shaft, a gear on said main driving shaft adapted to be meshed with the first mentioned gear and 105 means connecting said main driving shaft to said generator shaft whereby the said generator and its shaft may be removed from said mounting without disturbing the stub shaft and driving connections between 110 it and said main driving shaft, substantially as described.

11. In a device of the character described, 115 in combination, a mounting having two flanges and a housing integrally connected, an opening into said housing through one of said flanges, a generator having an end plate with a hub thereon and a driving shaft projecting through said hub, a bearing within said hub for said shaft, said hub and 120 shaft projection extending into the housing through the opening in said flange, and means for detachably fastening said generator to said flange, a support, said second flange adapted to be rigidly fastened to said 125 support, a second opening into said housing, a main driving shaft extending through said opening into the housing, and means for connecting said main driving shaft to said generator shaft, a stub shaft having a 130

gear thereon, a gear on said main driving shaft adapted to mesh with the gear on said stub shaft, a timer-distributer detachably fastened to one end of said stub shaft and 5 means serving as a bearing and thrust collar for the other end of said stub shaft, substantially as described.

12. In a device of the character described, in combination, a mounting having two 10 flanges and a housing integrally connected, an opening into said housing through one of said flanges, a generator having an end plate with a hub thereon and a driving shaft projecting through said hub, a bearing 15 within said hub for said shaft, said hub and shaft projection extending into the housing through the opening in said flange, and means for detachably fastening said generator to said flange, a support, said second flange adapted to be rigidly fastened to 20 said support, a second opening into said housing, a main driving shaft extending through said opening into the housing and means for connecting said main driving 25 shaft to said generator shaft, a stub shaft having a gear thereon, a gear on said main driving shaft adapted to mesh with the gear on said stub shaft, a timer-distributer detachably fastened to one end of said stub 30 shaft and means serving as a bearing and thrust collar for the other end of said stub shaft, a thrust bearing on the distributor end of said stub shaft adapted to be removed from said housing, whereby said stub 35 shaft and gear thereon may be removed without disturbing the driving means to said generator, substantially as described.

13. In a device of the character described,

in combination, a mounting having two flanges and a housing, a portion of which 40 is circular, a generator having a shaft extension projecting through one of said flanges and into said housing, an engine, the other of said flanges being adapted to fasten to said engine, a driving shaft extending from said engine into the opposite side of said housing, a stub shaft mounted within the circular portion of said housing, a timer-distributer removably mounted on 45 said stub shaft and means within said housing for drivingly connecting said generator and stub shaft to the shaft from said engine, the said generator being attached to the said flange and the said stub shaft being mounted in said circular part of said housing, where- 50 by either can be removed without disturbing the other, substantially as described.

14. In a device of the character described, in combination, a generator having a shaft extension, a timer-distributer having a shaft 55 extension, a mounting plate and means for mounting the said generator and timer-distributer thereon, a main driving shaft and means for connecting it to both said shaft extensions, said timer-distributer mounting 60 means being carried by said mounting whereby when said means are removed, said generator and its driving connectings are not disturbed.

In testimony whereof, I affix my signature 70 in the presence of two witnesses.

JULIUS H. RICHARDS.
